UNITED STATES PATENT OFFICE

FRED M. CARROLL, OF YONKERS, NEW YORK, ASSIGNOR TO THE TABULATING MACHINE COMPANY, OF ENDICOTT, NEW YORK, A CORPORATION OF NEW JERSEY

PRINTING MECHANISM FOR ACCOUNTING MACHINES

Application filed August 18, 1928. Serial No. 300,454.

This invention relates to printing mechanisms, in general, and more particularly to printing or duplicating devices therefor whereby impressions may be effected on one or more record sheets.

Heretofore, it has been proposed to effect printing by placing in juxtaposition and feeding simultaneously therewith a sheet coated with carbon or other material. After 10 a single run the carbon sheet was again utilized for effecting other copies and such operations were continued until the useful life of the carbon was extracted. After a single, or several runs, the carbon strip was usually 15 damaged by tears and was only obviated by using an expensive grade of paper. The present invention permits the use of inexpensive grades and proposes feeding the carbon strip in such a manner that all the useful life 20 is practically extracted during a single run.

It is then a broad object of the present invention to feed a printing or duplicating medium dissimultaneously with a record sheet in the same direction to thereby effect successive printing or duplicating impressions 25 through the same portion of the medium.

It is more specifically an object of the present invention whereby a contacting record sheet and an impression sheet may be fed 30 different extents during each machine operation.

It is also an object of the present invention to provide a construction whereby an additional copy may also be effected by means 35 of the usual inking ribbon and to provide an arrangement whereby the tendency to feed the duplicating sheet the same extent by frictional contact will be obviated.

It is also an object of the present invention 40 to provide an arrangement whereby more than one duplicate copy may be provided for and still obtain the same beneficial results as when a single copy is obtained.

These and other objects will be clear from 45 the following description which should be read in connection with the accompanying drawings, in which:

Fig. 1 is a cross sectional view of a printing and duplicating mechanism constructed 50 according to the present invention.

Fig. 2 is a view in side elevation showing the paper strip and duplicating strip feeding devices.

Fig. 3 shows an arrangement for effecting additional copies on supplemental record 55 sheets.

Similar reference numerals in all the above figures are employed to designate corresponding parts thereof.

For the purpose of illustration, the present 60 improvements are shown in connection with the Hollerith tabulating machine and more particularly to improvements therein described in the copending application of Fred M. Carroll, Serial No. 254,936, filed February 17, 1928. It is to be understood that the present improvements may be embodied in 65 other forms of machines, and the present showing is to be considered as illustrative rather than restrictive.

In the printing attachment, the printing devices whereby numerals representing items or the total of items may be printed comprises a plurality of groups of type bars 6, any one of which may be impelled by hammers 7 70 against a platen 8 to perform the printing function. Details of the printing devices are fully disclosed in the Lake Patent No. 1,879,268, dated May 24, 1921.

The paper strip 10 upon which impressions 80 are made from the type carriers 6 by an inked ribbon 9 is drawn from a storage roller 11, thence passes around fixed rollers 12 and 13, around a roller 14 carried by a pivoted arm 15, to a roller 16, also carried by an arm 85 17, thence over and under a series of fixed rollers 18a and then passes around a curved plate 18 which is rigidly secured to fixed portions of the machine. Said plate is arcuate-shaped and is concentric with respect to 90 the shaft which supports the platen 8. The forward portion of plate 18 terminates at 19, permitting the record strip to be drawn upwardly between the platen roll 8 and the inking ribbon 9.

The paper strip 20 upon which the impressions are made by a duplicating medium, such as the carbon strip 21 herein shown, is drawn from a storage roller 22 and likewise passes 95 around rollers 13, 14 and 16 to the fixed roll- 200

ers 18b and then passes downward inside of the curved plate 18 and in immediate contact with the platen roll 8. The carbon coated strip 21 is drawn from a storage roll 23, 5 passes around the foremost roller 18a, thence downwardly around platen roller 8, its duplicating surface being in direct contact with the record strip 20. Above the platen roll the record strips 10 and 20 pass to each side 10 of a fixed rod or roller 24 and above the rod 24 the strips are separated more widely by a fixed plate 25. The space between the strips intermediate the roller 24 and plate 25 form a storage portion 26 for the carbon strip 21. 15 Above the plate 25 the record strips extend upwardly to cooperate with a pair of feeding rollers 27. It will be obvious that as an accumulation of used carbon paper increases, it is prevented from rising upwardly to 20 operate with the feeding rollers 27 by the plate 25.

The printed record strips 10 and 20 may be disposed of in any suitable manner but preferably are rolled over a grid-shaped 25 frame 28 by a plurality of rollers 29 after which time the strips are severed by a pair of knives 30 which permit the strips to assume a horizontal stacked position.

The mechanism for effecting line spacing 30 operations to space the printed entries is fully disclosed in the copending application of F. M. Carroll, Serial No. 254,936, filed February 17, 1928, to which reference may be had for a more complete showing and description. 35 However, in order to obtain a better understanding of the present invention this portion of the apparatus will be briefly described herein.

The line spacing devices are under the combined control of a constantly rotated ratchet wheel 31 (Fig. 2) and a magnet 32. Pivoted by a stud 33 is a triple armed member 34, one arm of which carries a pawl 35 adapted to normally latch a pawl 36 and hold a tooth 37 40 thereof out of engagement with the interdental spaces of the constantly rotating ratchet wheel 31. When the latching relationship is established an extension 38 of the latching pawl 35 is adjacent an upward extension 39 of an armature 40 attracted by the magnet 32. When the magnet 32 is energized 45 extension 39 will strike extension 38 rocking pawl 35 to permit a spring 41 to be effective to rock pawl 36 to engage the tooth 37 with the ratchet wheel 31. This will result in rocking triple armed member 34 and through a 50 link 42 will rock a bell crank lever 43 and through the medium of a pawl 44 coacting with a ratchet wheel 45 attached to a shaft 46 55 to which the rearward feeding roller 27 is secured, the pairs of feeding rollers 27 will be rotated. This will result in feeding the paper strips 10 and 20 upwardly to suitably space the last printed entry from the succeeding 60 one. Restoring action of the parts which

turn the rollers 27 is afforded by a spring 47 which is effective to accomplish this after the tooth 37 is disengaged from the ratchet wheel 31. The latter function is effected by the co-action of a cam extension 48 with a stationary 70 pin 49 attached to a fixed plate 50, pin 49 gradually camming pawl 36 downwardly until it is subsequently latched by pawl 35.

Power for driving the various parts just described may be obtained by a motor 51 75 (Fig. 1) which drives a shaft 52 by a belt connection 53. The shaft 52 drives the ratchet wheel 31 continuously through the train of gears and pinions denoted by numeral 54 (see Fig. 2).

Pivoted to a downward extension of lever 43 is a gravity pawl 56 engaging the teeth of a ratchet wheel 57 so that the latter is adapted to be given a counterclockwise increment of movement as an incident to each printing operation, retrograde movement of said wheel being prevented by a pawl 58. The ratchet wheel 57 has secured thereto a grooved pulley 59 which drives a larger pulley 60 by a belt connection 61. The diametrical dimensions 85 of the pulleys 59 and 60 are so proportioned that the pulley 60 is rotated a very small amount and considerably less than the feeding rollers 27 during each machine operation. The pulley 60 has a suitable driving connection 90 to the roller 23 carrying the carbon sheet so that a predetermined but small amount is unrolled during each printing operation.

Referring to Fig. 1 it will be observed that as the feeding rollers 27 draw the record 100 strips 10 and 20 upwardly the strip 20 will tend to draw the carbon strip 21 upwardly with it since it is in frictional contact therewith around the platen roll 8. However, the resistance offered by suitable frictional devices, such as the belt connection 61 permits the carbon strip to be fed only an amount governed by the amount of turning imparted to the roller 23 by the pulley 60, and as previously stated, this is considerably less than the amount of feeding movement imparted to the feeding rollers 27. This permits the carbon strip to be wholly used up, since several impressions may occur over the same portion before it is passed on.

The used-up portion is drawn upwardly by the strip 20 and passes by the roller 24 so that it accumulates in the spaced portion 26 between the strips 10 and 20 and may be torn off when desired, roller 24 acting as a suitable 110 tearing edge.

It will be clear that if the strip 10 was also in immediate contact with the carbon strip 21, the tendency to feed the carbon strip an amount commensurate with the record sheets 125 would be augmented, and this could only be effectively prevented by providing additional braking or resisting devices which would probably result in placing such a strain upon the carbon sheet that it would tear or break. 130

The curved plate 18 prevents the undesirable frictional contact, and the only place where the record strip 10 of original entry contacts the carbon strip 21 is at or by the printing line and by suitably proportioning the position of the edge 19 and the plate 25 any desired frictional contact may be provided for, or eliminated entirely. Plate 25, as previously stated, prevents the used carbon sheet 10 from passing upwardly into cooperation with the record strip feeding rollers 27.

Fig. 3 indicates how the present system may be extended to effect additional carbon printed sheets and still realize the same beneficial results as heretofore. Record strip S1, associated carbon strip C1, and record strip S2 are arranged as previously described. In immediate contact with strip S2 is a supplemental carbon strip C2 which effects printing upon the former, thus producing a second carbon printed sheet. Strip S3 which is printed by means of the inked ribbon 9 is separated from the other sheets by an additional curved plate 181. Thus additional carbon printed copies, as desired, may be provided for.

While I have shown and described and pointed out the fundamental novel features of the invention as applied to a single modification it will be understood that various omissions and substitutions and changes in the form and details of the device illustrated and in its operation may be made by those skilled in the art without departing from the spirit of the invention. I intend to be limited therefore only as indicated by the scope of the following claims:

1. In a machine of the class described, comprising in combination with means for feeding a record strip to a printing line, means for feeding simultaneously therewith in the same direction but different extents an impression sheet physically contacting with said record strip whereby successive impressions are made through the same portion of said impression sheet.

2. In a machine of the class described, comprising in combination with means for feeding a record strip to a printing line, of means for feeding simultaneously therewith in the same direction an impression sheet physically contacting with said record strip, and a reduction mechanism for feeding said impression sheet a different extent whereby successive impressions are made through the same portions of said impression sheet.

3. In a machine of the class described, comprising in combination with a platen roll adapted to receive a record strip and a physically contacting impression sheet, means for rotating said platen roll to present successive but different portions of the record strip to a printing line, and means for feeding said impression sheet during the rotation of said platen a lesser extent to permit the same portion to be used for successive impressions.

4. In a machine of the class described comprising in combination with means for simultaneously feeding a pair of record strips of original and duplicating entry, of means for feeding a duplicating strip therewith, and means adapted to separate said record strips to provide a space to receive an accumulation of the duplicating strip.

5. In a machine of the class described comprising in combination with means for feeding a pair of record strips of original and duplicating entry, of means for feeding a duplicating sheet, and means whereby the duplicating entry receiving record strip physically contacts with the duplicating sheets only at the impression line.

6. In a machine of the class described comprising in combination with means for feeding a pair of record strips, of a duplicating sheet interposed between said record strips and adapted to physically contact with said strips only at the impression line, and means for simultaneously feeding said record strips and duplicating sheet different extents whereby successive impressions are effected from the same portion of the duplicating sheet.

7. In a machine of the class described, comprising in combination with means for feeding a record strip, of means for simultaneously imparting a like directional feed to an impression sheet physically contacting said record strip, and a reduction mechanism for feeding said record strip and impression sheet different extents.

8. In a machine of the class described, comprising in combination with a platen roll constituting one element of a printing couple adapted to receive a record strip, and an impression sheet physically contacting therewith, means for feeding the record strip and impression sheet simultaneously but different extents of movement, and means adapted to space a supplemental record strip apart from said platen roll.

9. In a machine of the class described, comprising in combination with a platen roll constituting one element of a printing couple for effecting impressions upon a pair of record strips, and means whereby said strips are spaced apart to permit an independent feed of a duplicating medium associated with and physically contacting one of said strips.

10. In a machine of the class described comprising in combination with a platen roll constituting one element of a printing couple and adapted to determine the printing line of a pair of record strips, and means whereby said record strips are spaced apart at each side of the printing line to provide for the independent feed of a duplicating sheet and a duplicating sheet receiving space.

11. In a machine of the class described comprising in combination with a platen roll constituting one element of a printing couple for effecting impressions from a pair of rec-

ord strips, means whereby said strips are spaced apart at one side of the printing line to permit an independent feed of a duplicating sheet associated with and physically contacting one of said strips but permitting the merging of said strips at the printing line of the platen roll, and means whereby said record strips are spaced apart at the other side of the printing line to provide a duplicating sheet receiving space.

10 In testimony whereof I hereto affix my signature.

FRED M. CARROLL.
